UNITED STATES PATENT OFFICE

129,391

DESIGN FOR A CYCLE HANDLEBAR SUPPORT FOR PADS, MAPS, OR THE LIKE

Joseph Fischer, Grand Rapids, Mich.

Application May 26, 1941, Serial No. 101,154

Term of patent 7 years

To all whom it may concern:

Be it known that I, Joseph Fischer, a citizen of the United States, residing at Grand Rapids, in the county of Kent and State of Michigan, have invented a new, original, and ornamental Design for a Cycle Handlebar Support for Pads, Maps or the Like, of which the following is a specification, reference being had to the accompanying drawing, forming part thereof, in which:

Fig. 1 is a plan view,

Fig. 2 a front elevation, and

Fig. 3 is an end elevation of a cycle handlebar support for pads, maps or the like, showing my new design.

I claim:

The ornamental design for a cycle handlebar support for pads, maps or the like, as shown.

JOSEPH FISCHER.
